US00D705790S

(12) United States Design Patent
Nations et al.

(10) Patent No.: US D705,790 S
(45) Date of Patent: * May 27, 2014

(54) DISPLAY SCREEN WITH GRAPHICAL USER INTERFACE

5,845,122 A 12/1998 Nielsen et al.
D409,590 S 5/1999 Newton et al.
5,909,548 A 6/1999 Klein et al.
5,949,887 A 9/1999 Fado et al.

(75) Inventors: Gregory M. Nations, Minneapolis, MN (US); Chad R. Gourley, Elk River, MN (US)

(73) Assignee: Target Brands, Inc., Minneapolis, MN (US)

CA 2714783 6/2011
CA 145715 8/2013

() Term: 14 Years

(21) Appl. No.: 29/409,743

OTHER PUBLICATIONS

(22) Filed: Dec. 28, 2011

Poem, "i carry your heart with me," by E. E. Cummings [on-line]; poem dated 1920. Retrieved from the Internet Aug. 1, 2013. URL: >https://en.wikipedia.org/wiki/E_E_Cummings<. (12 pages, see p. 5).*

(51) LOC (10) Cl. 14-04
(52) U.S. Cl. USPC D14/486
